UNITED STATES PATENT OFFICE.

HARRY O. RUGH, OF SANDWICH, ILLINOIS, ASSIGNOR, BY MESNE ASSIGNMENTS, TO HALL SWITCH & SIGNAL COMPANY, A CORPORATION OF MAINE.

CALLING DEVICE.

1,114,048.

Specification of Letters Patent. Patented Oct. 20, 1914.

Application filed September 1, 1910. Serial No. 580,068.

To all whom it may concern:

Be it known that I, HARRY O. RUGH, a citizen of the United States, residing at Sandwich, in the county of Dekalb and State 5 of Illinois, have invented a certain new and useful Improvement in Calling Devices, of which the following is a full, clear, concise, and exact description, reference being had to the accompanying drawings, forming a 10 part of this specification.

My invention relates to calling devices and has for its object the provision of a novel calling device for selective signaling circuits.

15 One of the features of the invention consists in the provision of means whereby the call sending element of the device may be operated to send a call for a predetermined station and the said element 20 may be thereafter successively operated to send calls for succeeding stations, without releasing the substation mechanisms between calls. This feature is of special utility in connection with step-by-step devices.

25 In my application Serial No. 574,584, filed July 29, 1910, I set forth a substation circuit also illustrated herein in which I use restoring means at each step-by-step element, which restoring means shown comprise a controlling magnet, the function of 30 the controlling magnet being to set a locking pawl into the step-by-step element during the signaling operation, but to release the locking pawl therefrom after the call 35 has been sent to thereby permit restoration of the elements to their normal position. It is of advantage to have these restoring means operative, if possible, before the signal sending device begins its step-by-step 40 action and my invention herein contemplates means whereby the calling device during its setting operation, that is during the time that it is being placed into position to begin its impulse sending operations, 45 operatively actuates the said controlling magnet or more broadly speaking the restoring means to place the substation devices in condition to be operated immediately the calling device begins its substation calling operations. The means herein 50 specifically illustrated which produce these results comprise an impulse sending relay under the control of an impulse sending element of the signal sending device and

switching apparatus whereby the relay is 55 energized as the step-by-step element is moved in one direction to thereby send a long impulse over the line to operatively actuate the release controlling magnet so that when the impulse element at the sending 60 station is released to send its impulses, the release controlling substation magnet has already placed the substation element in condition for operative forward movement immediately the impulses begin. The invention 65 also contemplates novel circuit changing mechanism to effect this result. The invention also contemplates novel means whereby the signal sending call box is placed upon a supporting plate and mating members associated therewith for effecting electrical contact so that a temporary defective 70 call box may be removed and another one inserted in place thereof without the necessity of elaborate or lengthy circuit connections. 75

I will describe my invention more in detail by reference to the accompanying drawings illustrating one embodiment thereof in which:

Figure 1 is a front view of my improved call box; Fig. 2 shows the removable mounting therefor upon its base with the interlocking circuit connections; Fig. 3 is a rear view of the cover showing the mechanism; Fig. 4 is a diagrammatic view of the circuit; Fig. 5 is a view similar to Fig. 3 showing the use of the instrument for calling succeeding stations; Fig. 6 is an end view of the call sending mechanism; Fig. 7 is a diagrammatic view of the type of substation apparatus which can be used in connection with my invention, and: Fig. 8 is a detail of one of the magnets used at the substation apparatus.

Like characters of reference indicate like parts throughout the different figures.

Referring more particularly to Figs. 1 and 2, I show a call box 1 having a cover 2, which cover carries a dial 3 used for signal sending purposes and under the control of a handle or finger hold 4. The dial 3 is provided with a plurality of apertures 5 depending upon the number of stations to be used in connection with the system. The finger hold 4 includes a knob 6 which is movable circumferentially so that a pin 7 provided upon the extremity of the knob may

be inserted in any aperture 5 and the dial then set to call the particular station desired.

The call box 1 is mounted upon a base 8 of insulating material, which base in the instance shown, has two plugs 9, 9 fastened thereto and in direct connection with the circuit over which the impulses are to be sent, two wires being all that are needed for connection with the call box. The call box itself has two sockets or jacks 10 mating or interlocking with the plugs 9 so that the call box may be set in place upon the supporting plate 8 and the plugs engage the jacks to make electrical connection with the interior of the call box through the agency of the springs 11, 11. Two binding posts 12 are also provided in case connection is desired to be made other than through the use of the plug and jack arrangement aforesaid.

In Fig. 2 the supporting plate 8 is shown in dotted lines to indicate that the call box is removable therefrom as desired and in the manner indicated. The two outside connections from the jacks preferably extend direct to the hinges 13, 13 and from them into the call box and to the mechanism as will be more clearly explained.

The dial is fastened to a shaft 14 which projects through the cover 2 and upon which an impulse element 15 is secured by means of the set screw 16. The impulse element is provided with teeth 17 in accordance with the number of stations for which the line is designed and has one elongated tooth 18 which is used finally to prolong the connection of signal sending current through the line wires after the proper station has been called, thereby to operate the substation signal.

It will be understood that I am describing herein specifically a form of carrying out my invention, not with any idea however that I am thereby indicating that my invention does not include a great many other forms in which it may be carried out.

The impulse element together with the dial after being set in a clockwise direction, referring to Fig. 1, are moved in a counter-clockwise direction to send the required impulses through the agency of a clockwork the details of which it is not thought necessary to explain, which clockwork however includes a spring 19, the governor 20 and suitable gear wheels 21 and 22 so that when the dial is moved in a clockwise direction the spring is wound up and returns the shaft 14 with its associated mechanism to the starting point. The impulse element 15 is in association with a spring 23, which spring is engaged by the teeth 17 and the elongated tooth 18, but is not in engagement with the element 15 except when in contact with such teeth aforesaid. The spring 23

is connected to the lower hinge 13 and the framework of the machine including the impulse element 15 is connected to the upper hinge 13. A frictional element 24 shown more clearly in side view in Fig. 6 is mounted upon the end of a spring 25 and carries frictional means such as rubber or leather 26. The spring 25 is adapted for engagement with either a spring 27 or a spring 28. When the impulse wheel 15, referring to Fig. 3, rotates in a clockwise direction it carries the frictional element along as said frictional element bears against said impulse element and thus connects springs 25 and 27 together, whereas when the impulse mechanism is moved in the opposite direction it brings springs 25 and 28 together. Spring 28 is directly connected to the lower hinge 13 and spring 25 to the frame of the machine so that when springs 25 and 28 are together, the same circuit conditions are established as when spring 23 engages the teeth 17 or tooth 18. This will be clear from Fig. 4 where the two wires 29 and 30 which lead out of the call box through the plugs 10, 10 are shown as connected to a battery 31 serially with a relay 32. When the spring 23 touches the teeth of the impulse element 15 the relay 32 is drawn up to attract its armature 33 to send impulses over the line wires 34 and 35 through the agency of the battery 36, these impulses corresponding to the impulses established by the engagement of the spring 23 with the teeth 17 or 18. Referring to Figs. 3 and 4 the impulse element, while the dial is being set to a position from which it begins its call sending operations, is moved in conjunction with said dial in a counter-clockwise direction or in the direction of the arrow as Figs. 3 and 4 are rear views with respect to Fig. 1. During this time, while the dial and impulse element are thus being set, springs 25 and 28 are in engagement and the relay 32 is permanently pulled up which sends a long impulse over the line wires 34 and 35 to thereby place the restoring or release controlling magnets at the substations in their operative positions, whereby a locking pawl is thrown into engagement with the teeth of the substation step-by-step elements. The substation step-by-step elements are then in condition to be immediately responsive to impulses from the impulse element 15 when it begins its reverse movement under the influence of the spring 19. Immediately upon starting the reverse movement the frictional element 24 opens the contact between springs 25 and 28 and causes contact to be made between springs 25 and 27, spring 27 in this instance serving merely as a holding spring.

It will thus be seen that as the dial is being set, a shunt circuit is placed about the circuit changing elements 23 and 15 so that

the movement of the teeth against the spring 23 does not influence the magnet 32, but immediately upon the beginning of the reverse movement of the dial, the magnet 32 is responsive to contact between the spring 23 and the teeth 17 and 18. It will thus be seen that the initial impulse to place the substation apparatus in condition to receive a signal is made while setting the apparatus and not while the dial is making its automatic signal sending movement. To fully understand this reference is had to Fig. 7 where the line wires 34 and 35 are shown as uniting three substations A, B and C, at each of which substations there is a restoring or controlling magnet 37, shown more in detail in Fig. 8, which controlling magnet has an energizing winding consisting of the coils 38 and a periodically short circuited secondary winding consisting of the coils 39 which control the armature 40 against the operation of a spring 41. The armature 40 is normally rapidly responsive to the establishment of current in the coils 38, but when the armature has once been drawn up it engages the contact 42 thereby establishing a short circuited secondary winding on the cores of said magnet so that the armature having once been drawn up, the magnet is slow acting and will not release its armature during momentary interruptions of the current in the coils 38 but will only release its armature 40 after the current has been discontinued a given length of time.

The magnet 37 controls a locking pawl 43 which is thrown into engagement with the teeth of the step-by-step element 44 when the long impulse is received over the line wires 34 and 35 while the dial at the call box is being moved to its initial signal sending position. Thereafter the impulses sent from the calling station are so rapid as not to influence the magnet 37, but they do influence the magnet 45 which, through the agency of its pawl 46, steps up the element 44 to establish contact between the elements 47 and 48 of the particular station desired. After the impulse element 15 in its return movement has sent the required impulses to call a predetermined station, the spring 23 engages the elongated tooth 18 which thereupon keeps both magnets 45 and 37 energized to maintain contact between the elements 47 and 48 a given length of time sufficient to permit battery 49 to operate the local signal 50. After this, the spring 23 leaves the tooth 18 and being no longer in contact with any portion of the impulse element 15, current is discontinued over the line wires 34 and 35 and after a discontinuance of such current for a brief interval, armature 40 of the magnet 37 is released, thereby permitting the withdrawal of pawls 43 and 46 from the step-by-step element 44 and permitting the spring 51 to restore said

element to their normal positions against the stop 52.

My invention further contemplates means whereby after one station is called, succeeding stations may be called without first restoring the step-by-step elements 44 to normal. These means include a push button 53 actuating a lever 54 to place it in a position whereby it engages a pin 55 mounted upon the reverse side of the impulse element 15. When the lever arm 54 thus engages the pin 55 as clearly shown in dotted lines in Fig. 5, the impulse element 15 instead of being stopped in the normal position indicated in Fig. 3 is stopped in the position indicated in Fig. 5 when the spring 23 has moved upon the tooth 18 just a sufficient distance equal to approximately one-half the width of a tooth 17. In this condition it is apparent that contact is maintained through the relay 32 and current is maintained on the line so that the substation mechanisms remain in the position to which they were moved by the impulses transmitted from the element 15, during which time the signal of the predetermined and called station continues to operate. Suppose that this were, for instance, the station A which responds to a given number of impulses and it is desired to also call station B which responds to a greater number of impulses and then station C which responds to a still greater number of impulses. Button 53 is actuated and the impulse element on its return is held in the position of Fig. 5. Then if it takes, for instance, two more impulses to call station B, the finger hold 6 is set into No. 2 of the dial and again actuated and the reverse movement of the element 15 sends the two additional impulses and the said element is again held in the position of Fig. 5. Then if station C is desired which may, for instance, respond to three more impulses than station B, the finger hold is set in No. 3 and the dial moved so that its return movement sends three impulses to call said station C. It will be understood of course that the dial has a normal position as shown in Fig. 1 and this is determined by a lug 56 which engages a lug 57 mounted upon the cover. A second lug 58 is provided which is designed to be engaged by the pin 7 to limit the movement to which the dial must be subjected in its setting operation. As will be apparent from the illustrations when station 1 is to be called and the finger hold 6 is placed in the hole 1 that the dial must move a distance equal to the length of the tooth 18 and to a point beyond the first tooth 17 so that one impulse is sent to step-up 125 the stations to the No. 1 position, whereafter the long impulse from the tooth 18 is being sent to operate the signal.

While I have herein shown and particularly described the preferred embodiment

of my invention, I do not mean to limit myself to the precise construction and arrangement as herein set forth, but

Having thus described my invention, what I claim as new and desire to secure by Letters Patent is:

1. A signal sending apparatus having a current impulse controlling device, an impulse sending relay under the control thereof, and auxiliary means for close-circuiting said relay during the movement of said device in one direction.

2. A signal sending apparatus having a current impulse controlling device, an impulse sending relay under the control thereof, and auxiliary means for close-circuiting said relay during the movement of said device in one direction and opening said closed circuit during the reverse movement to permit said impulse device to intermittently operate said relay during said reverse movement.

3. A signal sending apparatus having a current impulse controlling device, a relay for transmitting impulses operable thereby, and auxiliary means controlled by said device to operate said relay to send one prolonged impulse during the movement of said device in one direction.

30 4. A signal sending device comprising a circuit controlling current impulse controlling mechanism having means for transmitting a plurality of impulses followed by a prolonged impulse, means for moving said mechanism, and means for arresting the movement of said mechanism before the completion of the prolonged impulse aforesaid.

5. A signal sending device comprising a circuit controlling current impulse controlling mechanism having means for transmitting a plurality of impulses followed by a final impulse, means for moving said mechanism, and means for arresting the movement of said mechanism before the completion of the final impulse aforesaid.

6. A signal sending device comprising a current impulse controlling mechanism having means for transmitting a plurality of signal selecting impulses and a final signal operating impulse, means for moving said mechanism, and means for arresting the movement of said mechanism before completion of the final impulse aforesaid.

55 7. A signal sending apparatus having a movable current impulse controlling device, means for moving said device in one direction to set the same in condition to send a call for a pre-determined station, means for returning said device to its initial position whereby the selecting impulses are sent, means whereby said device may send a substation setting impulse during the setting movement of said device, and a relay for

repeating all of said impulses to a line circuit.

8. A call box having a movable element, means for setting said element in position to send a call for a pre-determined station, means whereby said element transmits impulses during its reverse movement, and means whereby a prolonged impulse is transmitted by said element throughout substantially the entire period of its setting operation.

7 9. A call box having a movable element, means for setting said element in position to send a call for a pre-determined station, means whereby said element during substantially the entire period of the setting 80 operation controls the transmission of a prolonged impulse, and means whereby said element during its reverse movement controls the transmission of a plurality of substantially selecting impulses.

10 10. A signal sending apparatus having a current impulse controlling device, a relay for transmitting impulses operable thereby, and means controlled by said device to establish a closed circuit through said relay 90 when said device is moving in one direction to thereby disable the relay for transmitting impulses in answer to the movement of said device.

11 11. A signal-sending apparatus having a movable current impulse controlling device, a relay under the control thereof and auxiliary means for short-circuiting the impulse controlling device during the movement of said device in one direction.

10 12. In a signal-sending apparatus, the combination of a toothed wheel having a setting movement and a reverse movement, a relay under the control thereof and means for close circuiting said relay during substantially the setting period of said wheel and means for intermittently close circuiting said relay during substantially the reverse movement of said wheel.

11 13. In a selective call device, the combination of an impulse member having two movements and means dependent upon the movement of said member for sending a pre-determined number of long and short impulses whereby the movement in one direction produces only long impulses, and movement in the other direction produces short impulses.

12 14. In a signal-sending apparatus, the combination of a toothed wheel adapted to 120 be moved in two directions, means whereby current impulses are produced during the movement of said wheel in one direction and means for shunting said impulse-producing means during the other movement 125 of said wheel whereby a single long impulse is produced.

15. In a signal-sending apparatus, the

combination of a toothed wheel adapted to be moved in two directions, a spring contact adapted to be engaged by each tooth, a relay, a circuit for said relay, one terminal of which is constituted by the teeth of said wheel and the other by said spring, whereby said circuit is closed when said spring is in engagement with a tooth and means adapted to shunt said teeth and spring 10 during one movement of said wheel and remove said shunt during the other movement of said wheel whereby said relay is energized during substantially the whole of one movement of said wheel and intermittently energized during the other movement thereof.

16. In a signal-sending apparatus, the combination of a toothed wheel adapted to be moved in two directions, a spring contact 20 adapted to be engaged by each tooth, a relay,

a circuit for said relay, one terminal of which is constituted by the teeth of said wheel and the other by said spring, whereby said circuit is closed when said spring is in engagement with a tooth and means adapted to automatically shunt said teeth and spring 25 during one movement of said wheel and remove said shunt during the other movement of said wheel whereby said relay is energized during substantially the whole of one 30 movement of said wheel and intermittently energized during the other movement thereof.

In witness whereof, I hereunto subscribe my name this fifteenth day of August A. D., 1910.

HARRY O. RUGH.
